DESIGN FOR A COMBINATION TRACTOR AND TRAILER

Harold H. Robinson, Opa Locka, Fla., assignor to Curtiss Aerocar Company, Inc., Opa Locka,
Fla., a corporation of Florida

Application March 27, 1933. Serial No. 47,598

Term of Patent 14 Years

To all whom it may concern:

Be it known that I, HAROLD H. ROBINSON, a citizen of the United States residing at Opa Locka, in the county of Dade and State of Florida, have invented a new, original, and ornamental Design for a Combination Tractor and Trailer, of which the following is a specification, reference being had to the accompanying drawings, forming a part thereof.

Referring to the drawings:

Fig. 1 is a side view of the combination tractor and trailer;

Fig. 2 is a top view thereof.

Fig. 3 is a front view of the trailer member of the combination; and

Fig. 4 is a rear view of the tractor member of the combination.

I claim:

The ornamental design for a combination tractor and trailer as shown.

HAROLD H. ROBINSON.
